FIG. 1 is a perspective view of a drilling tool showing my
new design, with a middle portion between dash-dot-dash
lines omitted.

FIG. 2 is a front view thereof, with a middle portion between
dash-dot-dash lines omitted,

FIG. 3 is a plan view thereof, with a middle portion between
dash-dot-dash lines omitted,

FIG. 4 is a left side view thereof;

FIG. 5 is a right side view thereof;

FIG. 6 is an enlarged left side view thereof;

FIG. 7 is an enlarged perspective view thereof;

FIG. 8 is an enlarged front view thereof;

FIG. 9 is an enlarged plan view thereof;

FIG. 10 is an enlarged left side view thereof; and,

FIG. 11 is a reduced front view thereof.

All broken lines shown in the drawings represent portions of
the drilling tool that form no part of the claimed design.

1 Claim, 5 Drawing Sheets
